UNITED STATES PATENT OFFICE.

ARTHUR J. FILKINS, OF RIVERSIDE, ILLINOIS.

PORTABLE LOCOMOTIVE-DRAFTING DEVICE.

1,165,957.

Specification of Letters Patent. Patented Dec. 28, 1915.

Application filed July 19, 1915. Serial No. 40,647.

To all whom it may concern:

Be it known that I, ARTHUR J. FILKINS, a citizen of the United States, residing at Riverside, in the county of Cook and State 5 of Illinois, have invented a new and useful Improvement in Portable Locomotive-Drafting Devices, of which the following is a specification.

My invention relates to certain new and 10 useful improvements in portable locomotive drafting devices, and is fully described and explained in the specification and shown in the accompanying drawings, in which:—

15 Figure 1 is an end elevation showing my improved device in its relation to a locomotive, and Fig. 2 is a rear elevation of the device.

Referring to the drawings, 3 is a platform 20 carried by a frame-work 4 and movable from place to place on wheels 5. Mounted on the platform is an exhaust fan or blower 6 driven by a motor 7. The intake or suction end of the fan is provided with an elbow 25 8 to which is pivoted a pipe 9 adapted to be raised and lowered by means of a rope 10 running over a pulley 11 carried by an upwardly projecting part 12 of the frame. The pipe 9 has at its upper end an elbow 30 13 which flares at its lower end and is provided on its rear side with a plate 14 adapted to coöperate with the front part of the flaring elbow to afford an inward conical surface to contact with and fit tightly over 35 the stack of a locomotive. The shape of the elbow is such that a fairly tight fit will be given even though there be a considerable variation in the relative position of the portable frame and locomotive, although it 40 will be understood that in operation this portable frame should be put in substantially the position illustrated.

The exhaust end of the blower or fan is connected to a pipe 15 over which is telescoped a pipe 16 which can be more or less extended through the medium of a rope 17 running over a pulley 18. The pipe 16 is of sufficient extent to run well up into the smoke-jacks commonly provided in round-houses to receive the discharge from the locomotives.

55 The present device is used in a round-house for the purpose of assisting in firing a locomotive. When it is desired to fire any given locomotive, the device is brought up alongside, the intake-pipe of the fan ad-

justed to fit with its flaring elbow over the smoke-stack and the exhaust-pipe of the fan is adjusted to extend up into the smoke-jack. The fan then starts to operate, producing in the locomotive the desired draft so that the firing takes place quickly and without inconvenience, and all the products of combustion are passed through the fan and discharged into the smoke-jack which is entirely capable of handling them in the ordinary way. As soon as the locomotive has a sufficient pressure of steam in its boiler that the forced draft can be used in the ordinary way, the present device is disconnected and moved to another locomotive which requires firing.

It will be observed that the present device is exceedingly simple in its construction, that it can readily be moved from 75 place to place so as to operate on a succession of locomotives, and that in this way at the very lowest expense it is possible to secure the desirable results of artificial suction in firing.

I realize that considerable variation is 80 possible in the details of the construction herein shown, and I do not intend to limit myself thereto, except as pointed out in the following claims in which it is my intention 85 to claim all the novelty inherent in the device as broadly as is permitted by the state of the art.

I claim as new and desire to secure by Letters Patent:—

1. A portable device for drafting locomotives when firing the same, comprising a platform movable from place to place, a power-driven fan thereon, means to connect the intake of the fan to the front end 95 of the locomotive, and means to lead the exhaust from the fan into the smoke-jack of the roundhouse.

2. A portable device for drafting locomotives when firing the same, comprising a 100 platform movable from place to place, a power-driven fan thereon, means to connect the intake of the fan to the smoke-stack of the locomotive, and means to lead the exhaust from the fan into the smoke-jack of 105 the roundhouse.

3. A portable device for drafting locomotives when firing the same, comprising a platform movable from place to place, a power-driven fan thereon, a pipe having 110 pivotal connection with the intake of the fan and adapted to swing down upon the

smoke-stack of the locomotive, and means to lead the exhaust from the fan into the smoke-jack of the roundhouse.

4. A portable device for drafting locomotives when firing the same, comprising a platform movable from place to place, a power-driven fan thereon, means to connect the intake of the fan to the smoke-stack of the locomotive and a telescoping pipe attached to the fan to lead the exhaust therefrom into the smoke-jack of the roundhouse.
5. A portable device for drafting locomotives when firing the same, comprising a platform movable from place to place, a power-driven fan thereon, means to connect the intake of the fan to the smoke-stack of the locomotive and a telescoping pipe attached to the fan to lead the exhaust therefrom into the smoke-jack of the roundhouse.

motives when firing the same, comprising a platform movable from place to place, 15 a power-driven fan thereon, a pipe having pivotal connection with the intake of the fan and adapted to swing down upon the smoke-stack of the locomotive, and a telescopic pipe attached to the same to lead 20 the exhaust therefrom into the smoke-jack.

ARTHUR J. FILKINS.
